UNITED STATES PATENT OFFICE.

WILLIAM ALEXANDER ANDERSON, OF SAN FRANCISCO, CALIFORNIA.

ROTARY DRILL.

Application filed November 27, 1922. Serial No. 603,641.

To all whom it may concern:

Be it known that I, WILLIAM ALEXANDER ANDERSON, a citizen of the United States, resident of San Francisco, county of San Francisco, State of California, have invented a new and useful Rotary Drill, of which the following is a specification.

The present invention relates to improvements in rotary drills adapted to be used for 10 boring purposes, especially wells and holes. My invention is designed particularly for the drilling of oil wells and offers particular advantages for this purpose, but it should be understood that I do not desire to limit 15 myself to this particular function but wish to be protected on my drill generally without reference to any particular kind of wells. The particular object of my device is to lessen the labor of such boring work, and to 20 reduce the cost of the apparatus. It is a well known fact that in the present practice of hydraulic rotary drilling the shaft carrying the bit extends from the bottom of the well to the surface of the ground and a cer- 25 tain distance above the ground so that it may be driven from a power plant which is supported independently of the shaft. In my device the power plant is brought into one unit with the shaft and moves down- 30 wardly with the same as the hole grows deeper so that it is unnecessary to extend the shaft, a flexible connection being main- 35 tained between the shaft and the power plant carrying unit and the surface of the ground whereby the unit may be pulled up- 40 ward when it is desired to change the bit or when the intended depth has been reached. A further advantage of my device is that it becomes exceedingly easy to change 45 the bits, and to take core samples of geological formations that the drill is passing through. In present day practice it happens quite frequently that the bit grows dull very quickly and its takes considerable time 50 to change the bit, increasing as the depth grows greater. My device comprises a single unit connected to a hoisting apparatus above the ground by means of a cable and a 55 hose and its takes very little effort on the part of the men as well as very little time to lift the unit out of the well and replace the bits or to take core samples of earth formation penetrated. A further object of 60 my invention is to provide means whereby the débris may be removed from the bottom of the well with very little difficulty, my

means being adapted for the flooding of the débris as well as for the removal of the same by air suction or pressure. The latter method is of particular importance where 60 water is rare and where it is desired to make a close study of the different strata passed by the drill.

With these and other objects in view I have illustrated the preferred form of my 65 invention in the accompanying drawings, in which Figures 1, 2, 3, 4 and 5 represent a vertical section through my device, Figure 1 showing the top portion, Figures 2, 3 and 4 the central portion and Figure 5 the bottom 70 portion, Figure 6 a horizontal section taken along line VI—VI of Figure 2, Figure 7 a bottom plan view, Figure 8 a vertical section along line VII—VII of Figure 2, and Figure 9 a sectional detail view of 75 an expansion chamber controlling the amount of oil contained in the device. While I have shown only the preferred form of my invention, it should be understood that various changes or modifications might be made 80 within the scope of the claims hereto attached without departing from the spirit of the invention.

The housing (1) of my device comprises a tube (2), an upper casting (3), closing 85 the top of the tube and secured in its place by means of screws (4) and a lower casting (6) closing the bottom of the tube and secured in its place by means of screws (7). I prefer to drive my drill by means 90 of an electric motor and therefor have confined my illustrations to that particular drive although it will be readily understood that other means for driving my drill may be used such as compressed air. A 95 particular feature of my invention is that I use two concentric shafts each of which carries a bit of its own and both of which are rotated simultaneously but in opposite directions at the same or different speeds. 100 These two shafts are run by the same motor or motors, one of them being connected with the armature of the motor while the other is driven by the field, both of which are rotatably mounted in the housing. Re- 105 ferring to the drawings it will be seen that the inner shaft (8) which is coupled in several places as at (8') and (8'') ex- 110 tends from the upper casting downwardly through the bottom casting and carries below said bottom casting the bit (9), while the outer shaft (11), coupled as shown at

(11') and (11'') surrounds the inner shaft concentrically so as to leave sufficient space between the same for the different windings and other devices hereinafter to be described and narrows at the bottom as shown at (12) so as to make a running fit on the inner shaft when it passes through the lower casting. The outer shaft also carries at the bottom a bit (13) disposed concentrically relative to the bit (9). The inner shaft is held in proper alignment by its engagement with the upper and lower castings as well as by suitable guides (14) provided with anti-friction bearings (16). The outer shaft is maintained in its position by means of suitable guides (17) and anti-friction bearings (18) reducing the friction to a minimum. A suitable thrust bearing (19) is provided below the body portion of the outer shaft to support the rotating field and armature, and another thrust bearing (21) above a collar (22) to bear against a guide (20) for holding the shaft against upward motion. It will be seen that suitable stuffing boxes (24) are provided in the top and bottom castings to prevent any leakages around the shaft. For driving the drill I preferably use one or more single-phase or polyphase induction motors, the armatures (26) being associated with the inner shaft while the fields (27) form a part of the outer shaft. Suitable wire connections may be made by brushes (28) engaging collecting rings (30). It will be readily understood that if neither the armature nor the field are held stationary, both of them will under normal conditions develop an equal tendency to rotate whenever electric current is supplied. The rotation of the armature will be in the opposite direction to that of the field so that when the motor is working the two bits (9) and (13) are rotated in opposite directions. It will be seen from Figure 5 that the bell shaped bit (13) surrounds the bit (9) and is set to cut in the opposite direction. Looking at the device from below the inner bit cuts on a rotation in a clock-wise direction while the outer bell-shaped bit cuts on a counter-clockwise rotation.

The inner shaft is hollow and extends, slightly reduced, through the upper casting, the upper portion being threaded as at (33) to receive the end of a hose not shown in the drawing. At the lower end of the inner shaft the bore extends through the upper portion of the bit (9) and finds two outlets (34) through the slanting sides (36) of the inner bit.

It has been noticed that under normal conditions the inner and outer shafts have an equal tendency to turn in opposite directions. But it will be understood that if one of the two bits carried on said two

shafts should meet with an obstacle such as a hard rock formation which would not affect the other bit this fact would have a natural tendency to slow down the bit meeting with the obstacle and might even cause the latter bit to become stationary, while the other bit would race correspondingly faster without doing any work. To overcome this I provide the device shown in Figure 6, by means of which the two shafts are connected to each other in such a manner that they have to maintain the same speed ratios. This device comprises an internal gear (37) associated with the outer shaft, an external gear (38) keyed to or integral with the inner shaft and a plurality of pinions (39) revolvably interposed between the two gears, the pinions revolving on stationary studs (41) extending downwardly from one of the stationary guide members (14) secured to the housing (1), which latter is held against rotation by means referred to hereinafter.

As long as both shafts have a tendency to run at the same speed ratios, the pinions (39) idle between the two gears (37) and (38). But as soon as one of the shafts develops a tendency, due to a lighter load, to rotate faster than the other one the pinions (39) become active and transmit any excess power from the shaft running under a lighter load to the other thereby assisting the latter and overcoming the obstacle referred to. In this manner both shafts are always forced to rotate at the same speed ratios and all the power transmitted to the shafts will be utilized.

To prevent the housing itself from rotating within the hole drilled I provide the device shown in Figure 1 comprising a yoke (42) secured to the top casting (3) by means of screws (43) in the yoke (42) are pivotally supported a plurality of links (46), the outer ends of the links on either side of the yoke being joined by bars (47). The top ends of the bars are connected to a central head (48) by pivoted arms (49) and the head is provided with an eye (51) adapted to receive a cable or wire rope connection not shown in the drawing, whereby the whole device may be lifted. As long as the device is supported by the attachment, which connects with a cable, the bars (47) are drawn inwardly to the yoke, which tendency, however, is opposed by the spring (52) surrounding the stem (53) extending downwardly from the head (48) through the top member of the yoke. The spring bears against the underside of the top member of the yoke and a nut (54) threadedly engaging the stem so that the tension of the spring may be adjusted. When the bits strike the bottom of the hole and the weight of the device is wholly or partially taken off the cable and the head

(48), the spring (52) forces the bars (47) away from the yoke into contact with the wall of the hole whereby the whole device is prevented from rotating.

As a particular feature of my device, should be mentioned my oil system. To prevent the device from collapsing due to external pressures or to internal pressures as well as to prevent leakages it is desirable that the space between the housing and the shafts be kept filled with oil or other fluid continuously. But since the oil may heat during the operation of the device it is at the same time necessary to provide means for allowing of expansion of the oil or fluid. For this purpose I provide the expansion chamber (56) shown in detail in Figure 9 which consists of a tubular cup (57) terminating at the bottom in a threaded nipple (58) adapted to be screwed into the top casting (3) and communicating with a passage (59) extending through the casting. A cap (61) slidably engages the cup and is normally pulled downwardly by a spring (62). When the oil or fluid, which may be forced into the housing through any suitable hole as at (63) in the lower end of the housing (see Figure 4) expands, it forces the cap upward until the latter clears a perforation (64) in the cup which allows any excess oil or fluid to run through the perforation (64). In this manner the housing is kept filled with oil or fluid continuously without exposure to injury by internal pressure caused by the expansion of the oil or fluid due to heat. Suitable means are provided which may consist of adjustable spring or weight tension on the cap (61) which will maintain the oil or fluid pressure against external pressures. This difference being under control by the above mentioned tension.

The operation of the device will be readily understood from the foregoing description. The whole device is suspended from a suitable derrick and the hose leading to the bore in the inner shaft as well as the electric connections are wound on suitable drums so that all three, the lifting cable, the hose and the electrical connections, can follow the drill as the latter recedes from the surface. After the device has thus been properly placed and begun to work hardly any further change is necessary since no shafts need to be coupled and the device is limited in its penetration only by the length of the cable holding it. If it becomes necessary to change the bits the whole device may be hoisted upward with very little loss of time. To remove the débris I either use hydraulic or pneumatic apparatus. The use of water does not involve any new features and it may be just briefly stated that the water is admitted through the hose referred to, to the inside of the inner shaft

and that it floods the débris out of the hole. This procedure may be preferably used where water is plentiful and where the pressure of water is needed to support the sides of the hole. Where these conditions do not prevail I preferably use pneumatic pressures for the removal of the débris.

I claim:

1. In a rotary drill of the character described, two concentric shafts having drill bits thereon formed to attack the bottom of a well in opposite directions, electro-magnetic means causing relative rotary motion of the two shafts and compensating means causing both shafts to rotate in predetermined relation irrespective of the load encountered by either shaft.

2. In a rotary drill of the character described, two concentric shafts having drill bits thereon formed to attack the bottom of a well in opposite directions, electro-magnetic means causing relative rotary motion of the two shafts and means associated with the two shafts for maintaining their respective speed ratio whereby power is transferred from one to the other in case the latter is subjected to a heavier load.

3. In a rotary drill, an electric motor having a revolving field and a revolving armature, drill bits attached to the field and the armature, a stationary casing surrounding the motor, and compensating means for the field and armature anchored to the casing for causing the field and armature to revolve at a predetermined speed ratio irrespective of load variations.

4. In a rotary drill, an electric motor having a revolving field and a revolving armature, drill bits attached to the field and the armature, a stationary casing surrounding the motor, a ring within the casing anchored to the same having pins extending from its face and pinions secured to said pins and an internal gear associated with the field and an external gear associated with the armature engaging said pinions for maintaining a predetermined speed ratio of the field and the armature.

5. In a rotary drill of the character described, a housing, a shaft and a motor actuating the same supported therein with freedom of rotary motion, and means associated with the housing for automatically maintaining and regulating internal pressure of a fluid against external pressure, said means comprising an expansion chamber communicating with the housing, a cap slidably engaging the same, and adjustable yielding means for seating the cap.

6. In a rotary drill of the character described, a housing, a shaft and a motor actuating the same supported therein with freedom of rotary motion, and means associated with the housing for automatically maintaining and regulating internal pres-

sure of a fluid against external pressure, said means comprising an expansion chamber communicating with the housing, a cap slidably engaging the same, adjustable yielding means for seating the cap and an outlet normally covered by the cap adapted to be cleared when the internal pressure exceeds a predetermined degree.

7. In a rotary drill, an electric motor 10 having a revolving field and a revolving armature, drill bits attached to the field and the armature, a casing surrounding the motor, compensating means for the field and armature anchored to the casing for 15 causing the field and armature to revolve at a predetermined speed ratio irrespective of load conditions and means for holding

the casing against rotation made to yield when upward pull is exerted thereon.

8. In a single unit rotary drill comprising a casing, a bit carrying shaft rotatable therein and a power plant for actuating the shaft mounted in the casing, means for holding the casing against rotation comprising a plurality of links pivoted to opposite sides of the casing, bars connecting the extreme ends of the links on either side, a central head, pivoted links connecting the latter to the bars and spring means tending to pull the head downwardly for forcing the bars into engagement with the wall of the well adapted to yield when the head is pulled upwardly for raising the casing. 25 30

WILLIAM ALEXANDER ANDERSON.
